(57) **CLAIM**

The ornamental design for an insole box, as shown and described.

DESCRIPTION

FIG. 1 is a front and top perspective view of an insole box, showing my new design in a position of use with an exemplary wrapper;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and top perspective view thereof, shown with the exemplary wrapper removed and further showing the insole box in a partially open configuration; and,

FIG. 10 is a front and top perspective view thereof, shown in an open configuration.

The broken lines in the figures illustrate portions of the insole box that form no part of the claimed design. The broken lines showing of the exemplary wrapper form no part of the claimed design.

1 Claim, 10 Drawing Sheets
